UNITED STATES PATENT OFFICE.

AUGUSTUS MAY, OF NEW ORLEANS, LOUISIANA.

DRIP-CUP FOR REFRIGERATORS.

932,878.

Specification of Letters Patent. Patented Aug. 31, 1909.

Application filed February 25, 1909. Serial No. 479,909.

To all whom it may concern:

Be it known that I, AUGUSTUS MAY, a citizen of the United States, residing at New Orleans, in the parish of Orleans and State 5 of Louisiana, have invented new and useful Improvements in Drip-Cups for Refrigerators, of which the following is a specification.

This invention relates to drip cups for refrigerators, ice-boxes and the like, and the objects of the same are to provide a device of this class which will efficiently carry off the drainage, exclude hot air from the interior of the refrigerator, ice-box or the like, 10 to prevent ingress of bugs and small insects into the refrigerator or cooling receptacle to which the cup is applied, and to preserve sanitary conditions within the refrigerator by having the cup removable and capable 15 of being readily cleansed.

In addition to the desirable functions in drip cup constructions just enumerated, the improved drip cup is conveniently accessible as it is disposed in position from the interior 20 of the refrigerator or like device and may be readily reached at any time and withdrawn and reset without requiring displacement of the refrigerator or cooling receptacle to which the improved cup is applied.

The improved drip cup essentially comprises two elements, namely, an outer containing receptacle or member, and an inner drainage directing or delivery receptacle which is rotatably disposed in the outer receptacle or member, both of these devices being tubular and removable from the refrigerator or other cooling device. As a secondary feature a smaller drainage tube extends downwardly into the inner tubular receptacle and may project any distance above the top of both receptacles or terminate approximately in a plane coincident with the top of the inner rotatable receptacle in accordance with the particular requirements 30 of different refrigerator or ice-box constructions and the mode of applying the improved drip cup thereto.

The invention also consists in the construction and arrangement of the several parts which will be more fully hereinafter specified.

In the drawing: Figure 1 is a sectional view of a portion of a refrigerator showing the improved drip cup applied thereto and 40 also illustrated in section and as having the drainage pipe extending from a point above

the location of the drip cup, as for instance in communication with the ice chamber, not shown. Fig. 2 illustrates detail perspective views of the drip cup members or elements 60 disassociated and constructed for use with an ordinary refrigerator having the ice chamber at an elevation above the bottom of the refrigerator. Fig. 3 is a horizontal section taken through the inner and outer tubular 65 members of the drip cup as shown by Figs. 1 and 2, and illustrating the openings in both members in registration. Fig. 4 is a view similar to Fig. 3 showing the inner member turned within the outer member 70 and the openings in the two members out of registration. Fig. 5 is a sectional view of the form of drip cup particularly adapted for use with ice boxes or refrigerating devices wherein the ice is disposed against the 75 bottom, a portion of the ice box or analogous device being shown by Fig. 5. Fig. 6 is a detail elevation, partially in section, showing a modification of the construction illustrated by Fig. 1 and particularly relating to 80 the drain tube section or connection between the cup and drip pipe of the refrigerator. Fig. 7 is a detail view in sectional elevation showing a further modification relating to the structure shown by Fig. 1. Fig. 8 is a 85 detail plan view, partially in section, showing a modification of the structure illustrated by Fig. 5.

The numeral 5 designates a refrigerator of any suitable construction having a storage chamber 6 for articles desired to be preserved by refrigeration. Projecting downwardly into the chamber 6 is a drip or drainage pipe 7 which terminates and communicates at its upper end with the usual ice 90 chamber, not shown. In the bottom 8 of the refrigerator an opening 9 is formed at any point desired, and therein is fitted an outer tubular member or containing receptacle 10 having a lower closed bottom 11, an 100 opening 12 in the side thereof at a point above the bottom, and an upper open end 13 having a horizontal flange or rim 14 with a packing or gasket 15 secured against the under side thereof and of any suitable material. The packing or gasket 15 is adapted to be snugly and tightly held against the upper surface of the bottom 8 around the upper extremity of the opening 9, as shown 105 by Fig. 1.

Within the tubular member 10 an inner tubular member 16 of smaller diameter is 110

2
rotatably mounted and has a fully open bottom 17, an opening 18 at a distance above the lower end thereof to register with the opening 12 in the member 10, and an upper cap 19 having an outwardly projecting circumferential flange 20 with a packing or gasket 21 applied to the under side thereof and similar to the packing or gasket 15. The gasket or packing 21 is adapted to tightly bear on the upper surface of the flange 14 at the upper end of the member 10 and form a tight joint with said flange.

10 Eccentrically formed in the cap 19 is an opening 22 through which extends the lower portion of a drainage tube section 23 telescopically fitted or applied to the drip or drainage pipe 7 and having at an intermediate point a circumferential stop flange 24 with a gasket 25 of suitable material fixed 20 against the under side thereof to bear on the cap 19 over the opening 22 and thereby close the latter opening and also maintain the lower portion of the drainage tube section 23 projected a predetermined distance 25 downwardly within the inner tubular member 16. The lower end of the drainage tube section 23 is fully open, but the remaining part of such section is imperforate and the drip or drainage water flows downwardly 30 through the said section 23 into the outer tubular member 10. A water seal 26 is provided within the outer tubular member or receptacle 10 below the opening 12 and fully covering the lower extremity or open end of the drainage tube section 23, this water seal 35 being maintained at all times and excluding exterior warm air from the interior of the refrigerator and also preventing the ingress of bugs or insects and surrounding impure gases. The accumulation of drainage or 40 drip water within the cup is gradually relieved by overflowing through the opening 12, the latter constituting an outlet, and from the said outlet the drainage water 45 overflowing from the cup may fall into a suitable receptacle or other means placed under the cup. Insects, noxious odors or gases, and heated air currents are prevented from passing into the refrigerator above the 50 water seal by the several packings or gaskets 15, 21 and 25 bearing respectively on the bottom 8 of the refrigerator, the flange 14 of the outer tubular member, and the cap 19 of the inner rotatable tubular member.

55 When it is desired to remove the cup, the tube section 23 is pushed upwardly over the drainage pipe 7 far enough to clear the members 10 and 16, and the member 16 is then rotated in the member 10 to turn the opening 60 18 out of registration with relation to the opening 12 to prevent the water from slopping out through the outlet opening when the outer and inner tubular members are 65 unitedly withdrawn or removed from the opening 8 upwardly into the refrigerator

and outwardly through the door of the latter, and which operation may be readily accomplished after the tube section 23 is elevated or disengaged from the said members, and said tube section can also be disengaged 70 from the pipe 7 and likewise withdrawn from the refrigerator. The members 10 and 16 after withdrawal may be separated and thoroughly cleansed and reassembled and placed in position in the opening 9 from the 75 interior of the refrigerator and the tube section reinserted in place, and subsequently the said tube section 23 may be readily drawn downwardly and inserted through the opening 22 and projected into normal 80 position within the two tubular members 10 and 16, it being understood that the member 16 will first be turned or rotated to again bring its opening 18 into registration with the opening 12. 85

The modified form of the device as shown by Fig. 5 is particularly intended for application to ice boxes or analogous cooling receptacles wherein the ice is placed directly on the bottom of the receptacle or so close 90 to the said bottom as to render the use of tube section 23 impracticable, and in this instance an opening 27 is formed in the bottom 28, and at the upper extremity of the opening is a countersunk seat 29. The tubes 10 and 16 are of the same construction and have the same detail arrangement as illustrated by Figs. 1 and 2, and like reference numerals are applied thereto. The inner tube 16 in this instance, however, is without 100 the upper cap 19, but has an annular flange 30 therein below the upper end of the same to receive the upper flanged end 31 of a drain tube section 32, the flanged end 31 being surrounded by a packing 33 to closely 105 bear on the annular flange 30, and over the upper end of the drainage tube section 32 is a foraminous or perforate covering or strainer 34.

As shown by Fig. 8, the cap 19 has a grip 110 or handle 35 movably attached thereto for facilitating withdrawal of the inner tube 16 from and redisposition of said tube in the outer tubular member or containing receptacle 10, and in this instance also the 115 foraminous or perforate covering or strainer 34 on the upper end of the drain tube section 32 has a locking or retention bar 36 disposed thereover to hold the same down in place, the said bar 36 having removable engagement with reversely projected clips 37 arranged at opposite points on the cap 19 and operating to positively hold the drain tube section 32 and its strainer 34 in associated 120 relation to the inner tube 16 during withdrawal or insertion of the said inner tube with relation to the outer tubular member or containing receptacle 10 and until manual release ensues. 125

In the modified form of the device shown 130

by Fig. 6, the construction is similar in all respects to the form of the cup shown by Figs. 1, 2, 3 and 4 with the exception that the drain tube section 23 is shorter than illustrated by Figs. 1 and 2, and between the said shorter drain tube section 23 and the drip pipe 7 of the refrigerator an auxiliary coupling or connecting section 23^a is interposed, the latter section being telescopically fitted on the drain tube 7 and movable upwardly and downwardly over the latter to disconnect or assemble the same with relation to the upper end of the shorter tube section 23. By this means the drip cup with the tubular section 23 therein may be withdrawn from and inserted in the refrigerator without separating the said tube section from the inner tube 16 and outer tubular member or containing receptacle 10. In operating this form of the device it is only necessary to push the auxiliary tube section 23^a upwardly over the drain pipe 7 to disconnect the lower end of said tube section from the upper extremity of the tube section 23 in withdrawing the cup from the refrigerator, and after the cup is reset in the refrigerator, connection with the drip or drain tube 7 may be readily accomplished by drawing the auxiliary tube section 23^a downwardly and causing the lower end of said auxiliary tube section to enter the upper end of the tube section 23, the auxiliary tube section 23^a being provided with a circumferential flange 23^b to bear snugly against the upper end of the tube section 23.

In the modified construction shown by Fig. 7, the drain tube section 23 is similar to that shown by Figs. 1 and 2, and thereon is fitted a weight 38 which bears against the flange 24 of the said drain tube section and operates to maintain the said flange and the washer 25 in close contact with the cap 19 of the inner tube 16 and also to hold the flange 20 and washer 21 of the cap 19 downwardly on the flange 14 of the outer tubular member or containing receptacle 10, and, furthermore, to establish a tight joint between the flange 14 and its washer 15 with the upper portion of the wall of the opening 9 of the refrigerator. In other words, the weight 38 positively holds the separable parts of the cup in tight assemblage and prevents the cup parts from becoming accidentally disassociated or occupying loose positions, one with relation to another. In this construction when the drain tube section 23 is separated from the inner tube 16 it is elevated or pushed upwardly over the drain tube 7 against the resistance of the weight 38, and after reassemblage of the cup with the opening in the refrigerator the tube section 23 is reinserted in the inner tube 16 and the weight establishes a tight joint between the assembled parts of the cup, as just explained.

The improved device in its several forms

may be applied to refrigerators and ice boxes or analogous devices now in use at a minimum expense, and the saving in the consumption of ice and other conveniences accruing from the use of the improved drip cup as hereinbefore enumerated will render the first cost of application of no moment. It is preferred that the several parts of the cup, including the drainage tube sections used in each instance, be formed of tin, zinc or galvanized iron or any other non-corrosive material adapted for the purpose and the gaskets, packings, or washers are preferably formed from rubber.

The improved cup is exceptionally convenient and readily accessible and in view of the specific construction hereinbefore explained will be found strong and durable and practically impossible for it to get out of order. Being easily detachable and applicable in operative position, and composed of separable parts, any one of the parts may be replaced by another of like construction in the event of injury thereto to such an extent as to render it impractical without requiring a replacement of the entire cup structure. Further, in view of the fact that the several parts of the cup are separable and may be thoroughly cleaned, the propagation of disease germs is prevented and the cup as a whole may be maintained in perfect sanitary condition at all times with very little trouble. It will also be understood that changes in the proportions and dimensions of the cup may be adopted at will to adapt the same to various applications.

What is claimed is:

1. A cup for the purposes specified consisting of an outer tubular containing member having an outflow opening above the lower extremity thereof, an inner tubular member rotatably mounted in the outer member and having a fully open lower end and an opening therein above the lower end to register with the outlet opening in the outer member, and a drainage tube section removably mounted in the said members.

2. A cup for the purposes specified consisting of outer and inner tubular members, the inner member being rotatable in the outer member and the outer member having a closed bottom and an outlet opening, and a tubular drainage means projecting downwardly into the two members, a water seal being adapted to be formed below the outlet opening of the outer member and over the lower extremity of the inner tubular member and drainage tube section.

3. A cup for the purposes specified consisting of outer and inner tubular members having gaskets at their upper bearing extremities to form tight joints in relation to each other and the device to which they are applied, the outer member having a closed

- bottom and an outlet opening above the bottom and the inner member rotatable in the outer member and having a fully open lower end and also provided with an opening to register with that in the outer member, and a tubular drainage section projecting downwardly into the two members and also having a gasket to form a tight joint with the upper end of the inner member all of the parts of the cup being separable for cleaning purposes.
4. The combination with a cooling receptacle having a bottom opening, of a cup for the purposes specified removably inserted in the said opening from the interior of the receptacle and comprising separably associated outer and inner tubular members and a tubular drainage section projecting into said members, the outer and inner members having openings in the sides above the bottoms thereof and the inner member rotatable in the outer member.
5. The combination with a cooling receptacle having a bottom opening and a drainage pipe disposed over said opening, of a drip cup removably inserted in the said opening from the interior of the receptacle and comprising separably associated outer and inner tubular members and a tubular drainage section projecting into said members and telescopically fitted over the drainage pipe, the outer and inner members having openings in the sides above the bottom thereof and also provided with upper gaskets to form tight joints at their

upper ends, the tubular drainage section also having a gasket to form a tight joint with the upper end of the inner member.

6. The combination with a refrigerating receptacle having an opening therein, of a drip cup removably inserted in the said opening from the interior of the receptacle and comprising separably associated outer and inner tubular members and having tubular drainage means communicating with said members, the outer and inner members having openings in the sides above the bottoms thereof and the inner member rotatable in the outer member.

7. The combination with a cooling receptacle having a bottom opening and a drainage pipe disposed over said opening, of a drip cup removably inserted in the opening from the interior of the receptacle and comprising separably associated outer and inner tubular members and having tubular drainage means communicating therewith and telescopically fitted over the drainage pipe, the outer and inner members having openings in the sides above the bottom thereof, and a weight means engaging a portion of the tubular drainage means.

In testimony whereof I have hereunto set my hand in presence of two subscribing witnesses.

AUGUSTUS MAY.
